FRANK L. FITHIAN, OF HADDONFIELD, NEW JERSEY.

FOUNTAIN ATTACHMENT FOR PENS.

1,192,511.

Specification of Letters Patent. Patented July 25, 1916.

Application filed October 5, 1915. Serial No. 54,146.

To all whom it may concern:

Be it known that I, FRANK L. FITHIAN, a citizen of the United States, and resident of Haddonfield, county of Camden, and 5 State of New Jersey, have invented an Improvement in Fountain Attachments for Pens, of which the following is a specification.

This invention relates to fountain attachments for pens and has for an object to provide a simple and effective device which is adapted to be removably attached to an ordinary writing pen for the purpose of collecting and holding a quantity of reserve 10 ink, whereby the pen in use is automatically supplied with ink for a considerable period and in a uniform manner without redipping in the ink well.

It has for a further object to provide a 20 fountain attachment formed of spring metal, so arranged and constructed as to provide the device with means for removably clamping the attachment to the body portion of a pen, and also having means for 25 exerting a clamping action upon the tapering side edges of the pen whereby the device, while readily removable, is held in its operative position in use as a substantially permanent part of the pen.

30 A further object is to provide an attachment for pens wherein the construction is such as to form a clamping means acting laterally against the side edges of the pen and between which a tongue of spring material is located having the double function 35 of forming a holding means for the ink and also guiding and delivering the ink to the pen point.

With the above and other objects in view, 40 the nature of which will be more fully understood from the description hereinafter, the invention consists in the novel construction of fountain attachments for pens as hereinafter more fully described and defined 45 in the claims.

Referring to the drawings: Figure 1 represents a longitudinal section of a pen showing the fountain attachment of my invention mounted thereon; Fig. 2 represents 50 a bottom plan of the same; Fig. 3 represents a top plan thereof; Fig. 4 represents a section on line 4—4 of Fig. 3; Fig. 5 represents a bottom plan of a pen showing a modified form of the attachment; Fig. 6 55 represents a bottom plan of the pen showing another embodiment of the fountain attach-

ment; Fig. 7 represents a longitudinal section of the device shown in Fig. 6; and Fig. 8 represents a bottom plan of a pen showing another modification of the fountain attachment. 60

The fountain attachment of the present invention in its preferred form consists of a single piece of wire bent into suitable form so that it may be readily placed and 65 held by its own resiliency in operative position upon a pen to form a retaining means for the ink so that the pen may be used for a considerable amount of writing without redipping into the ink well. 70

1 designates a pen, which is of ordinary form, and to which the fountain attachment, designated generally by the reference numeral 2, is removably secured. The wire forming this attachment has its two terminals 3 bent rearwardly above the body portion of the device in such a manner that when placed upon the pen the said terminals rest substantially longitudinally upon the top or upper surface of the pen, as will be 80 seen in Fig. 3.

By reference to Figs. 1 and 2, it will be noted that the wire from each of the terminals 3 extends downwardly around the edges of the pen and below the bottom or concave 85 portion thereof, thence rearwardly and longitudinally to substantially parallel the said terminals 3. At suitable points within the body of the pen these rearwardly extending portions are reversely bent to form fingers 90 at 4, the inner end portions of which are bent upwardly toward the lower surface of the pen, as shown at 5; and when the attachment is removed from the pen, these end portions 5 of the fingers are substantially in 95 contact with the terminals 3 owing to their resiliency or spring action. In view of the fact that the wire is preferably of spring material, this construction affords a means of retaining the attachment in place upon 100 the pen, since the insertion of the pen between the terminals 3 and ends 5 forces the said parts to separate and each therefore grips the pen body with an effective clamping action. The continuation of the wire 105 forming the fingers 4 provides a centrally disposed loop or tongue 6 located between the opposite sides of the fingers and preferably being upwardly bent as shown at 7 toward the lower surface of the pen in order 110 to terminate in close proximity thereto and properly coöperate with the parts 8 for the

purpose of feeding the ink toward the pen point. The main or body portion of the attachment is of a width less than the width of an ordinary pen, in order that the device 5 may readily be slipped into position over the point of the pen and so that the fingers and terminals properly engage the body portion of the pen and occupy a portion of the concaved part of the pen.

10 Since the point of an ordinary pen is of tapered construction, I have preferred to converge the side wires of the fingers as they approach the point end of the pen and provide an offset inwardly disposed curved 15 jaw 8 at each edge of the pen, the normal tendency of which is to spring together when released from the pen. These jaws 8 are therefore forced apart slightly by the wedging action of the pen point when the 20 device is slipped upon the pen, and thus form an auxiliary clamping means to prevent displacement of the device when in use.

By reference to Fig. 1 it will further be 25 seen that the upwardly turned parts 5 and 7 form with the body of the pen a substantially cup-shaped reservoir or receptacle which is adapted to retain a quantity of ink when the pen is dipped in the well and re- 30 moved in the usual manner. While this fountain receptacle is of substantially open construction to permit free flow of the liquid toward the pen point, the parts are, however, arranged in such relatively close relation that 35 there is sufficient capillary action as to prevent an excessive or flooding flow of the ink when the device is in use.

In Fig. 5 I have shown a modified form of the attachment wherein each terminal 3 40 passes from the upper surface of the pen, forming the offset curved jaws 8, to the lower surface where each part is wound into a substantially spiral form as shown at 10, the respective spirals being joined by an upwardly extending loop 11 designed to exert 45 the required clamping action as previously described for the parts 5.

In Fig. 6 another modification of the device is shown, wherein one of the end portions of the wire is provided with a spiral 50 as shown at 12, while the opposite portion is relatively straight as shown at 13 and joins the spiral by the loop portion 14.

Figs. 7 and 8 illustrate another embodiment of the invention wherein the wire forming the attachment is provided with a single loop 15 lying within the lower concave portion of the pen and having its end inclined upwardly to provide a required 60 clamping action with the upper terminals 3 of the device, the said loop 15 having mounted thereon a clip 16 which forms with the pen body a suitable receptacle for the ink. This clip is provided at one end with a forwardly projecting tongue 17 suitably bent

into close proximity with the surface of the pen for the purpose of guiding and delivering the ink toward the pen point, as will be understood. The said tongue 17 lies substantially between the offset jaws 8 of the 70 attachment, being substantially in alinement with the longitudinal axis of the pen to properly direct the ink toward the point.

The device is properly secured to a pen in a removable manner so that it may be 75 readily attached to any pen for use, and in its operative position clamps the body of the pen between the terminals 3 and the lower coacting parts, while the spring jaws passing around the edge of the pen are arranged to exert a lateral gripping action to further assist in holding the device in operative position. It will be apparent that this lateral gripping action is capable of adjustment in that the wedge effect of the 80 tapered edges of the pen serves to spread or open the jaws, thus varying the pressure of the jaws in accordance with the position of the device relative to the pen. The tongue member, which occupies a position substantially between the sides of the fingers, serves to feed the ink toward the point of the pen as well as retaining a stored quantity of the 85 ink for use according to requirements.

I have shown my improvements in the 90 form preferred, and yet the shapes of the parts and bends may be modified without departing from the spirit of the invention.

Having now described my invention, what I claim as new and desire to protect by Letters Patent is:

1. As a new article of manufacture, a fountain attachment for pens, comprising a wire of metal bent to form clamping members engaging respectively the upper and lower surface of a pen and providing laterally acting spring jaws for engaging the side edges of the pen and also a tongue between the jaws substantially alined with the longitudinal axis of the pen for guiding ink 105 toward the point of the pen.

2. As a new article of manufacture, a fountain attachment for pens, comprising a wire bent to form longitudinally disposed end portions lying along the upper surface of a pen and longitudinally disposed fingers lying along the lower surface of the pen, said fingers having upwardly disposed end portions adapted to clamp the pen against 115 said upper members, the wire between the respective upper and lower portions being bent to form offset laterally disposed jaws adapted to clamp the side edges of the pen and said fingers providing a tongue adjacent to the jaws adapted to feed the ink between 120 said jaws toward the point of said pen.

3. As a new article of manufacture, a fountain attachment for pens comprising a wire of spring material bent to form end portions adapted to seat longitudinally upon 130

the upper surface of a pen, each end portion being bent laterally and downwardly beneath the body of the pen to provide lateral clamping jaws and extended rearwardly and 5 longitudinally to form a pair of fingers, said fingers being bent upwardly to provide means to clamp said pen against the upper end portions and also being reversely bent to form a longitudinally disposed tongue 10 extending toward the jaws for the purpose of feeding the ink toward the point of the pen.

4. As a new article of manufacture, a fountain attachment for pens comprising a wire of metal bent to form end portions 15 adapted to seat longitudinally upon the upper surface of a pen, each end portion being bent laterally and downwardly beneath the body of the pen to provide jaws to laterally clamp the pen and extended rearwardly and longitudinally to form a pair of fingers, said fingers being respectively bent upwardly to clamp said pen against the upper end portions and also being reversely 20 bent to form a longitudinally disposed tongue said tongue having its end upwardly bent toward the jaws whereby it may terminate in close proximity to the under surface of the pen, so that the ink is fed from 25 said device toward the point of said pen.

5. As a new article of manufacture, a fountain attachment for pens comprising a wire of metal bent to form members adapted 30 to seat upon the upper surface of a pen and members adapted to seat against the lower surface of said pen, said sets of members being arranged to clamp against the pen by 35 spring action, the respective upper and lower members being connected by laterally

disposed jaws adapted to engage the side edges of the pen, whereby said attachment is removably clamped to said pen.

6. As a new article of manufacture, a fountain attachment for pens comprising a wire of metal bent to form a set of members 45 adapted to seat upon the upper surface of a pen and a set of members adapted to seat against the lower surface of said pen, said sets of members being arranged to clamp against the pen by spring action, the 50 respective upper and lower members of said sets being connected by laterally disposed jaws adapted to engage the side edges of the pen, and said lower set of members provided with means to retain a body of ink. 55

7. As a new article of manufacture, a fountain attachment for pens comprising a wire of metal bent to form a set of members adapted to seat upon the upper surface of a pen and a set of members adapted to seat 60 against the lower surface of said pen, said sets of members being arranged to clamp against the pen by spring action, the respective upper and lower members of said sets being connected by laterally disposed 65 jaws adapted to engage the side edges of the pen, and said lower set of members provided with means to retain a body of ink, comprising an extended body surface terminating in a tongue directed toward the jaws 70 of the two sets of members.

In testimony of which invention, I hereunto set my hand.

FRANK L. FITHIAN.
